UNITED STATES PATENT OFFICE

131,148

DESIGN FOR A COMBINED CARBIDE HOPPER AND FEED CONTROL UNIT FOR AN ACETYLENE GENERATOR

Willis G. Schepman, Indianapolis, Ind., assignor
to Oxweld Acetylene Company, a corporation
of West Virginia

Application November 28, 1941, Serial No. 104,362

Term of patent 14 years

To all whom it may concern:

Be it known that I, Willis G. Schepman, a citizen of the United States, residing at Indianapolis, in the county of Marion and State of Indiana, have invented a new, original, and ornamental Design for a Combined Carbide Hopper and Feed Control Unit for an Acetylene Generator, of which the following is a specification, reference being had to the accompanying drawing forming a part thereof.

Fig. 1 is an elevational view of a combined carbide hopper and feed control unit for an acetylene generator illustrating my new design;

Fig. 2 is an elevational view of the unit taken 90° from Fig. 1; and

Fig. 3 is a top plan view of the unit shown in Fig. 1.

The dominant features of my design reside in the portions of the drawing shown in full lines.

I claim:

The ornamental design for a combined carbide hopper and feed control unit for an acetylene generator, substantially as shown and described.

WILLIS G. SCHEPMAN.
